MOVABLE SUPPORT FOR DISPENSING
BEVERAGES

Jean Raoul Picard, Marseilles, France

Application October 12, 1933, Serial No. 693,355
In France October 21, 1932

10 Claims. (Cl. 225—22)

The subject of the invention consists of a movable support, particularly intended to be placed and to function in an establishment for serving drinks; bar, cafe etc. Its main object is to group, within easy reach of the assistant, all the bottles from which drinks are being served, and to facilitate the service for him, as he no longer has to go looking on shelves for the beverage required, to prevent obstructions on the counter, the inevitable soiling of the neck of the bottles by reason of their multiple handling, the shaking up of the liquor in its own bottle by reason again of these handlings, and to give to each consumer the exact quantity of the beverage chosen, determined automatically with the maximum of speed and cleanliness.

The support is characterized by the grouping of all the bottles in service placed upside down, thus permitting a flow from them, and by the facility given to turn it on itself for the purpose of replacing empty bottles.

This support is represented on the attached drawings, given by way of an example of construction of one of the forms of the subject of the invention.

In these drawings

Figure 1 shows, with parts intentionally cut, the support seen from the front in its normal position for delivering from the bottles which it supports;

Figure 2 shows the same support seen from the side;

Figure 3 is the plan view with parts again intentionally cut;

Figure 4 represents the support seen from the side in the reversed position, permitting the easy replacement of empty bottles.

The support consists of the vertical pillars 1 (Figures 1, 2 and 3) preferably tubular, fixed by known means to the feet 2, themselves fixed to the soleplates 3 attached to the counter 4. On the upper part of each of the pillars 1 is fixed a nut 5 in which screws a stem 6 operated by a knob 7. This stem 6 is attached by a ring 5' to a sleeve 8 fitting with slight friction over the tube 1. This sleeve carries a disc 9 having a conical surface 10 on which rests a corresponding surface mounted on the piece 11 carrying the bosses 12 into which penetrate the ends of each of the tubes 13, 14, 15 and 16 (Figure 3). The pieces 11 are held on the disc 9 by means of a pin 17 (Figure 3) carrying a nut 18 for ensuring the adjustment of the piece 11 on the conical surface 10. A screw 19, seen in Figure 3, permits by its displacement the release or immobilization of the moving pieces 11 on the fixed disc 9, into which it penetrates by the openings 20 drilled for this purpose.

On each of the tubes 13, 14 and 15, fixed respectively in the bosses 12 of each of the pieces

11, are arranged supports 21 (Figures 1 and 2) furnished at their lower part with a measuring distributor 22, of known type and operation, while at their upper part these same supports 21 are furnished with a clamping device 23 having an adjustable opening, and whose purpose is to grip firmly the bottle 24 without breaking it, and thus to maintain it with its neck in perfect contact with the measuring distributor 22.

The parts 11 also carry the tube 16, and this more particularly carries the control levers (Figure 4) 25 and 26 as well as the lever 27 actuating the screw 19, which also serves to drive the parts 11 which are displaced by a rotary movement on the disc 9.

The movable support for serving and distributing beverages thus formed, functions in the following manner:

At the instant when the bottles 24 are placed in position on the support, this must necessarily occupy the position shown in Figure 4; it is maintained in this position by the screw 19 penetrating the orifices 20 (Figure 3) pierced in the periphery of the disc 9. Each of the bottles 24, previously uncorked, is firmly supported against the orifice of the distributor 22 by the pressure of the clamp 23. When once all the bottles 24 have been suitably arranged on their individual support 21, all that is then necessary to put them in the serving position is to pull the lever 25 in the direction of the arrow 30 which, by the tube 16, displaces the levers 27 on which bear the nuts 29 of the springs shown in Figure 3, which become stretched, and thus to withdraw the extremity of the screw 19 from the orifice 20, thereby enabling the parts 11 to turn freely round the fixed disc 9 attached to the sleeves 8.

By continuing the pull on the lever 25 this displaces the parts 11 in the direction of the arrow 30 and the raising takes place. The operator might, however, experience certain difficulties in continuing to use the lever 25 to complete the displacement of the parts 11. In order to avoid this difficulty the lever 26 has been provided which, after having moved a certain distance with the parts 11, comes into proximity with the hand in the lower part of the apparatus, and thus enables the operator to continue the displacement of the parts 11 under the same conditions until the instant when the extremity of the screw 19 again encounters an orifice 20, and the release of the spring 29 (Figure 3) taking place will thus effect the penetration of the screw 19 into this orifice, thereby automatically arresting the parts 11 in the serving position shown in Figure 2.

By operating the knobs 31 each measure 22 will be actuated and the quantity of a given liquor will be served to the consumers.

As soon as a bottle 24 is empty it is only necessary to

sary for the operator to pull the lever 26 (Figure 2) in the direction of the arrow 30 to bring about first of all, by the displacement of the lever 27, the withdrawal of the screw 19, which releases 5 the supporting apparatus, and then to exert a pull in the direction of the arrow 32, the object of this being to displace the parts 11 in the direction of the arrow 33, in order to place the supporting apparatus once more in the position indicated in Figure 4. As soon as this change has 10 been made, the same phases of raising are reproduced, which have just been explained.

By the displacement of the screws 6 shown in Figure 1, it is possible to regulate the height of 15 the support for the bottles in such a way that the attendant can, without fatigue, get at each of the knobs 31 of the measures, and it also permits the consumer to see the person who is serving him and also to see the label of the beverage 20 for which he has asked.

A known damping device is provided for the discs 9 in order to reduce the effects of the impulse due to the weight of the bottles placed on the support at each of its displacements.

25 The shapes and the dimensions of the movable support may be varied without this in any way changing the general arrangement of the invention just described.

What I claim and desire to secure by Letters 30 Patent of United States is:—

1. Apparatus for dispensing liquids comprising a vertical support, a transverse bar carrying a liquid measuring and dispensing device, means for clamping a bottle on said bar with its open 35 end in communication with said measuring and dispensing device, means for rotating said bar relatively to said vertical support and means for locking said bar against rotation to hold the bottle carried thereby in either upright or inverted 40 position.

2. Apparatus for dispensing liquids comprising a columnar support, a flanged disc secured to said support a plate-like member having a conical portion rotatably secured to said flanged 45 disc, a transverse bar secured to said plate-like member and carrying a liquid measuring and dispensing device, means for clamping a bottle on said bar with its open end in communication with said measuring and dispensing device, means for rotating said plate-like member and means for locking said plate-like member to said flanged disc whenever the bottle has assumed 50 either an upright or inverted position.

3. Apparatus for dispensing liquids comprising a columnar support having a sleeve secured to its upper end said sleeve carrying a flanged disc, a plate-like member having a conical portion secured to and rotatable relatively to said flanged disc, a transverse bar carried by said plate-like 55 member, a bottle support carried by said bar, means for rotating said plate-like member relatively to said flanged disc and means for locking the said plate-like member to said flanged disc to hold the bottle support in either upright or inverted position.

4. Apparatus for dispensing liquids comprising a columnar support having a vertically adjustable sleeve secured to its upper end, said sleeve carrying a flanged disc, a plate-like member having a conical portion secured to and rotatable 70 relatively to said flanged disc, a transverse bar carried by said plate-like member, a bottle support carried by said bar, means for rotating said plate-like member relatively to said flanged disc and means for locking the said plate-like mem- 75

ber to said flanged disc to hold the bottle support in either upright or inverted position.

5. Apparatus for dispensing liquids comprising a columnar support, a vertically adjustable sleeve carrying a flanged disc secured to said support, a plate-like member having a conical portion rotatably secured to said flanged disc, a transverse bar secured to said plate-like member and carrying a liquid measuring and dispensing device, means for clamping a bottle on said bar with its open end in communication with said measuring and dispensing device, means for rotating said plate-like member and means for locking said plate-like member to said flanged disc whenever the bottle has assumed either an 15 upright or inverted position.

6. Apparatus for dispensing liquids comprising a columnar support, a flanged disc secured to said support a plate-like member having a conical portion rotatably secured to said flanged 20 disc, a transverse bar secured to said plate-like member and carrying a liquid measuring and dispensing device, means for clamping a bottle on said bar with its open end in communication with said measuring and dispensing device, means for rotating said plate-like member and means for locking said plate-like member to said flanged disc whenever the bottle has assumed either an upright or inverted position and means 25 operable by said rotating means to release the locking means and permit the rotation of the bottle.

7. Apparatus for dispensing liquids comprising a vertical support, a transverse bar carrying a liquid measuring and dispensing device, means 35 for clamping a bottle on said bar with its open end in communication with said measuring and dispensing device, means for rotating said bar relatively to said vertical support and means for locking said bar against rotation to hold the 40 bottle carried thereby in either upright or inverted position, said locking means being releasable by the actuation of the means for rotating the bar.

8. Apparatus for dispensing liquids comprising 45 a pair of vertical supports, a plate-like member pivotally connected to each support, transverse bars connecting said members, a liquid measuring and dispensing device carried by each bar, means for clamping a bottle on each bar 50 with its open end communicating with said measuring and dispensing device, means for swinging said members and bars about their pivots and means for locking said members to hold the bottles in either upright or inverted 55 position.

9. Apparatus for dispensing liquids comprising a pair of vertical supports, vertically adjustable sleeves on each support each sleeve carrying a disc, members having conical portions pivotally secured to and cooperating with said discs, transverse bars connecting said members, a liquid measuring and dispensing device secured to each 60 bar means for clamping a bottle to each bar with its open end communicating with said measuring and dispensing device means for locking each said disc to its cooperating member and means for simultaneously releasing said locking means and rotating said members.

10. Apparatus as claimed in claim 3 wherein said locking means comprises a rod adapted to engage in registrable apertures in said member and disc.
